[57] CLAIM

The ornamental design for an IC card reader and writer, as shown and described.

DESCRIPTION

FIG. 1 is a front elevational view of IC card reader and writer showing our new design thereof;

FIG. 2 is a right side elevational view thereof;

FIG. 3 is a top plan view thereof;

FIG. 4 is a bottom plan view thereof;

FIG. 5 is a rear elevational view thereof;

FIG. 6 is a left side elevational view thereof; and,

FIG. 7 is a perspective view of our new design for an IC card reader and writer showing for illustrative purposes only a card, in broken line, of a type useable with the IC card reader and writer, which card does not form a part of our design.
